William E. Currie,
Peter de Vries,

UNITED STATES PATENT OFFICE

WILLIAM E. CURRIE AND PETER DE VRIES, OF DETROIT, MICHIGAN; SAID DE VRIES AS
SIGNOR TO SAID CURRIE

CATTLE STANCHION

Application filed December 21, 1927. Serial No. 241,504.

The present invention pertains to a novel stanchion constructed for the purpose of retaining cattle in a given position and preventing their escape therefrom.

5 The principal object of the invention is to provide a device of this character having the advantages described in my co-pending application Serial No. 196,669, filed June 6, 1927, but by a simpler form of construction.

10 The operative parts of the present device include a head supporting a pair of spaced, pivotally mounted neck bars, provided at their upper ends with arms pivoted thereto and to each other. On displacement of the 15 common pivot point between the arms, the neck bars are swung relatively to the head to enlarge or diminish the space therebetween into which the neck of the animal is to be received. The invention further provides a simple mechanism for displacing the 20 above mentioned pivot point in the manner desired, and this mechanism is preferably controlled by an operating lever.

The invention is fully disclosed by way 25 of example in the following description and in the accompanying drawing, in which—

Figure 1 is a front elevation of the device in closed position;

Fig. 2 is a section on the line 2—2 of Figure 1; and

Fig. 3 is a section on the line 3—3 of Figure 1.

Reference to these views will now be made by use of like characters which are employed 35 to designate corresponding parts throughout.

The device is supported in a frame consisting of a base member 1, a pair of uprights or standards 2 secured thereto, and a pair of rails 3 fixed across the standards in the same horizontal plane and near the upper ends thereof. A hollow head 4, preferably a metallic member, is suspended from the rails by a pair of chains 5 attached to opposite sides thereof and anchored as at 6 in the rails.

45 Within the hollow member are pivotally mounted a pair of neck bars 7 in such a manner that the upper ends thereof are free and protrude above the upper edge of the head 4 as shown in Figure 1.

50 Several holes 8 are formed through the

head for accommodating the pivot pins 9, whereby the normal spacing between the neck bars may be varied according to the particular adjustment. The upper ends of the bars are bifurcated as at 10 for the purposes of receiving arms 11 pivotally connected therein by pins 12. The arms 11 extend inwardly of the bars and have their inner ends pivotally connected to each other by a pin 13. The outer ends of the arms are also provided each with a series of apertures 14 for selectively receiving the pins 12, whereby the spacing of the bars 7 may be further adjusted.

55 An arm 15 has one end pivotally supported between the rails 3 and the other end provided with a depending link member 16 which forms a box or socket 17 as shown more clearly in Figure 2. A clip 18 is pivotally held by the pivot pin 13 previously mentioned and is equipped with a ball 19 received in the 60 socket 17 so that a universal joint is provided between the parts 16 and 18.

65 The uprights 2 carry clips 20 above the rails 3, and in these clips is slidably mounted an operating rod 21. A link 22 pivoted at 70 both its ends connects the rod to the pivot point between the arm 15 and the link member 16.

75 From one of the standards 2 extends a bracket 23 having an operating lever 24 pivoted thereto intermediate its ends. One end of the lever is attached as at 25 to the rod 21 while the other end is provided with a handle 26. It will be apparent that by means of the operating lever the rod 21 may be slid across the frame, in consequence of which the link member 16 will be raised or lowered according to the direction in which the operating lever is swung. This action results in a lifting or lowering of the arms 11 at their common pivot point, so that the neck bars 7 will be expanded or contracted beneath the head 4 according to the direction in which the operation is performed.

85 The lower ends of the neck bars are provided with chains 27 attached to rods 28 on the base member 1 for the purpose of anchoring these ends and yet permitting movement thereof during the operations already described.

In the use of the device, the normal spacing of the bars 7 according to the size of the animal is determined by adjusting the pins 9 and 12 in the selected apertures 8 and 14. In order to release the animal, or to initially permit him to enter the device, the operating lever 24 is moved to the dotted line position shown in Figure 1, whereupon the common pivot point of the arms 11 is displaced and the bars 7 are caused to diverge beneath the head 4. In locking the animal between the bars, it will be obvious that a reverse movement of the lever 24 will close the bars on the animal's neck. The opening or expanding operation cannot be initiated at the bars 7 for the reason that such movement of the bars will tend to lower the common pivot point of the arms 11, which now decline towards this pivot point, and will cause the point to bear upon a heavy plate 29 secured on the upper edge of the head 4.

Although a specific embodiment of the invention has been illustrated and described, it will be understood that various alterations 25 in the details of construction may be made without departing from the scope of the invention as indicated by the appended claims.

What we claim is:—

1. A stanchion comprising a frame, a fixed rail included in said frame, a swingable head suspended from said rail, a pair of neck bars pivoted to said head, arms pivoted to said bars and pivotally connected together, and means for displacing the common pivot point 35 of said bars, whereby to swing said bars relatively to said head.

2. A stanchion comprising a frame, a fixed rail included in said frame, a swingable head suspended from said rail, a pair of neck bars 40 pivoted to said head, arms pivoted to said bars and pivotally connected together, an arm pivoted to said rail, a link connecting said last named arm to the common pivot point of the first named arms, and means for swinging 45 said last named arm on its pivot point, whereby to swing said bars relatively to said head.

In testimony whereof we affix our signatures.

WILLIAM E. CURRIE.
PETER DE VRIES.
